DESIGN FOR A RING MOUNTING

Frederick J. Kuczajda, Detroit, Mich.

Application March 20, 1944, Serial No. 112,966

Term of patent 14 years

(Cl. D45—10)

To all whom it may concern:

Be it known that I, Frederick J. Kuczajda, a citizen of the United States, residing at 5502 Livernois Avenue, city of Detroit, in the county of Wayne and State of Michigan, have invented a new, original, and ornamental Design for Ring Mounting, of which the following is a specification, reference being had to the accompanying drawing, forming part thereof.

In the drawing

Fig. 1 is a plan view of a ring mounting showing my new design;

Fig. 2 is a front elevation of the same;

Fig. 3 is a left side elevation of the same; and

Fig. 4 is a right side elevation of the same.

I claim:

The ornamental design for a ring mounting, as shown,

FREDERICK J. KUCZAJDA.
